MATCH BOOK

Paul Marach, 6361 Marquette St., Montreal,
Quebec, Canada
Filed May 29, 1963, Ser. No. 284,158
2 Claims. (Cl. 206—29)

The present invention relates to a match book and has for its main object the provision of a match book which is adapted to be removably secured to a cigarette pack of standard construction without in any way altering the construction of said cigarette pack, such as to form a combined cigarette pack and match book which can be easily inserted and carried in one's pocket.

Another object of the present invention resides in the provision of a match book of the character described, which can be easily affixed to any surface, such as the dashboard of an automobile, an ashtray, or the like.

An important object of the invention resides in the provision of a match book in which the matches are completely enclosed and cannot be ignited by a flying spark, whereby the match book is very safe to use.

Yet another important object of the present invention resides in the provision of a match book of the character described, in which the tail ends of the matches are disposed in staggered relationship, so that each match may be easily pulled off the match book to remove the same and without dislodging the remaining matches.

The foregoing and other important objects of the present invention will become more apparent during the following disclosure and by referring to the drawings, in which:

FIGURE 1 is a perspective view of the match book of the present invention, attached to a standard cigarette pack which is partially shown;

FIGURE 2 is a cross-section of the cigarette pack and end elevation of the match book, the section being taken along line 2—2 of FIGURE 3;

FIGURE 3 is a longitudinal section of the assembled match book and cigarette pack and taken along line 3—3 of FIGURE 2;

FIGURE 4 is a plan view of the top of the inner member defining the housing of the match book;

FIGURE 5 is a plan view of the bottom of the outer member defining the housing of the match book;

FIGURE 6 is an end elevation of the match book showing the side flanges in folded back position, which is the condition in which the match book is sold; and

FIGURE 7 shows an end elevation of the match book with the side flanges outwardly bent, with the match book shown adhered to a support surface.

Referring now more particularly to the drawings in which like reference characters indicate like elements throughout, the match book in accordance with the present invention comprises an inner housing member 1, an outer housing member 2, and a plurality of individual matches 3, all these elements being preferably made of cardboard material.

Inner housing member 1 has, in blank form, the shape shown in FIGURE 4; it comprises a generally rectangular piece of sheet material provided with two spaced longitudinally extending, parallel score lines 4 defining a web part 5 and side flanges 6; the ends of said side flanges 6 are preferably bevelled, as shown at 7.

The marginal end portions of the top face of web part 5 are coated with a layer 8 of pressure adhesive.

Outer member 2 consists also of a sheet of cardboard material of elongated shape and provided with two spaced, parallel, longitudinally extending score lines 9 defining between themselves a web part 10 and, on the outside thereof, side flanges 11 which have end bevelled edges 12 and which are provided in the center thereof with a V-

2

shaped notch 13, the apex of which coincides with the associated score line 9.

The underface of the end marginal portions of the web part 10 are coated with a layer of pressure adhesive 14. Each housing member 1 and 2 is folded about its score lines 4 and 9 respectively so as to form a member of U-shaped cross-section; the inner member 1 is nested within the outer member 2 with the side flanges of both members in contact and adhered condition, there being an intermediate layer of glue 15 between said pair of side flanges.

The two web parts 5 and 10 are spaced one from the other to define a space or housing, together with the side flanges, which is open at both ends thereof, as shown by openings 16. This housing receives the matches 3.

As shown in FIGURE 3, the matches 3 are preferably disposed in two groups of two rows each. The head or ignitable end 3' of the matches of the two groups faces each other within the center part of the housing, while the tail end 3'' of the two groups protrudes outwardly from the housing at both ends thereof through the openings 16.

The matches of each row are disposed side by side in a substantially common plane, but are completely separate from each other. The matches of the outer row are staggered with respect to the matches of the inner row, such that the tail end 3'' of the matches of the outer row protrudes outwardly from the tail end of the matches of the inner row.

The matches are maintained in position within the housing in the following manner:

The matches of the upper row removably adhere to the layer 14 of pressure adhesive on the inside face of the outer housing member 2, while the matches of the inner row removably adhere to the layer of pressure adhesive 8 on the top face of the inner housing member 1. The depth of the housing in the central part thereof is greater than its depth in the zone of openings 16 in order to accommodate the head ends 3' of the matches 3. This is obtained by slightly longitudinally folding the web 10 of the outer housing member 2 and fitting the same over the inner housing member 1; thus, the edges of the V-shaped notches 14 of the side flanges 11 are brought together.

The bottom face of the inner housing member 1 is preferably completely covered with a layer of pressure adhesive 17. The match book is further provided with a match igniting strip 18, which is preferably positioned to adhere to the outside face of a side flange 11 of the outer housing member 2 as shown in FIGURE 1, said strip 18 extending across the slit provided by the edges of the notch 13.

The customer will buy the match book in the condition shown in FIGURE 6 with the side flanges 6, 11 folded back about score lines 4 and 9 against the inner face of the inner housing member 1. The side wings or flanges 6, 11 are held in this position due to the adhesion provided by the layer of pressure adhesive 17. The user simply opens up the side flanges 6, 11, and the match book can be fitted with web part 5 over the edge face 20 of a standard cigarette pack 21 and with the inside faces of the side flanges 6 overlying the main faces 22 of the cigarette pack.

The match book is removably adhered to the cigarette pack due to the presence of the layer of pressure adhesive 17.

The distance separating the side flanges 6 is approximately equal to the width of the edge face 20 of the cigarette pack 21, said width being standard for "hard" packs of 20 and 25 cigarettes.

The match book can also be removably affixed to any "soft" type cigarette pack by changing its dimensions, if necessary.

One can also affix in a removable manner the match book in accordance with the invention to any underlying surface 23, as shown in FIGURE 7. The side wings provided by the flanges 6 and 11 are just folded outwardly and adhered to surface 23 by means of adhesive.

If matches still remain after emptying of the cigarette pack associated therewith, the match book can be removed therefrom and affixed to a new full cigarette pack.

While a preferred embodiment in accordance with the present invention has been illustrated and described, it is understood that various modifications have been resorted to without departing from the spirit and scope of the appended claims.

What I claim is:

1. A match book adapted to be secured to a cigarette pack, having a pair of main faces and an end face, comprising inner and outer housing members of sheet material and of U-shaped cross-section to form a web portion and side flanges, said housing members nested one within the other with said side flanges in direct and adhered contact and with their web portions spaced from each other to define a housing opening to the exterior at both ends thereof, the web portion of said outer housing member consisting of two mutually-inclined parts and having its apex in the central plane transverse to said housing, and a group of matches inserted through each opening, each match having a tail end portion protruding outwardly from the associated opening with the ignitable ends of the matches of the two groups in adjacent relation in the middle zone of said housing, said middle zone having

a greater depth than the zones of said openings, means to removably attach said matches in said position in said housing, said match book, when in secured position on said cigarette pack, having the web of said inner housing member overlying said edge face, and said side flanges overlying said main faces in pack embrasive relation, means to secure said match book to said pack, and a match igniting strip secured to the outside of said outer housing member.

2. A match book as claimed in claim 1, wherein the matches of each group are disposed in superposed rows, the tail end of the matches of an overlying row protruding outwardly relative to the tail ends of the matches of an underlying row.
